AMPLIFIER CONTROL

Frank Rieber, San Francisco, Calif., assignor, by
mesne assignments, to Sound Laboratory Cor-
poration, Ltd., a corporation of Nevada

Application July 3, 1929, Serial No. 375,871

8 Claims. (Cl. 179—171)

This invention relates to an amplifier system, and especially to an automatic control thereof whereby the degree of amplification is maintained below an undesired value.

5 Amplifier systems are now in quite general use for a variety of purposes. They can be used in transmitting and receiving signals either by wire or radio; and such signals can be telegraphic or speech signals. Furthermore, the systems can 10 be used for simple audio frequency signals, or for amplifying the carrier frequency impulses which are modulated by such audio frequency signals. Such amplifier systems are also useful in connection with recording and reproducing 15 sound, as is now common for example in connection with talking motion pictures.

In all such cases, it is advantageous to ensure 20 against too great a response of the apparatus to the signals; for otherwise serious injury may be done to the delicately adjusted apparatus; or else extremely great distortion of the signal may 25 result. As an instance where such great response would be annoying and harmful, attention may be called to the photographic recording of sound 30 for talking pictures. When the sound reaching the microphone is very loud, the light valve used in the recording system may be destroyed; and even for moderately loud signals, the system serves to distort them.

35 It has been proposed to guard against these effects by manual controls of potentiometers or other forms of control equipment. However, even the most attentive and expert operator is yet subject to the usual physiological response delay. Furthermore, such close attention and care is 40 required that the operator cannot maintain a uniformity of proficiency.

It is one of the objects of my invention, therefore, to make it possible to regulate the degree 45 of response in a manner independent of manual operation, and yet without distortion of the signals.

50 My control system can be easily adapted to work with the common types of electronic emission amplifiers. Such amplifiers usually include an evacuated vessel enclosing a plurality of electrodes. One of the electrodes is an electron emitting electrode, or cathode, and is usually, but not necessarily, in the form of a filament heated by an electric current. The electrons thus emitted are received on an anode also enclosed in the vessel and in the form of a plate. This anode is maintained at a potential positive with respect to the filament, as by the aid of a source of potential located in a circuit externally connecting

the two electrodes. The positive potential impressed on the plate serves to cause it to attract the electrons, which flow from the cathode and constitute the "space current".

It has been found that the space current can 5 be varied by large amounts by varying the potential difference, even by small amounts, between the cathode and a point in the space between the two electrodes. This variation in potential difference can be accomplished by the 10 aid of a control electrode interposed between the other electrode, and usually in the form of a grid. Weak signal impulses are caused to produce variations in potential between the cathode and the control electrode, and cause corresponding large 15 variations in the space current. It is in this way that an amplifier effect is secured. The amplified variations present in the "output circuit" (that is, the external circuit between the cathode and anode), can, if desired, be reamplified, by the 20 provision of succeeding amplifier stages.

Since such electron emission devices are now well understood, there is no need for any further detailed description of operation. It may, however, be mentioned that it is also common to 25 "feed back" some of the energy in the output circuit to the input circuit to produce reamplification by the aid of the same tube, and this process is usually termed "regeneration".

It is another object of my invention to provide 30 an automatic amplification limiter that can be used with electron emission amplifiers.

It is still another object of my invention to make it possible to limit the degree of regeneration obtainable by the aid of an electronic emission 35 amplifier; and in fact to make it possible automatically to reverse the regenerative effect when the amplification tends to become still greater. Thus a stabilizing result is provided that ensures against the production of parasitic 40 oscillations.

My invention possesses many other advantages, and has other objects which may be made more easily apparent from a consideration of one embodiment of my invention. For this purpose I 45 have shown a form in the drawing accompanying and forming part of the present specification. I shall now proceed to describe this form in detail which illustrates the general principles of my invention; but it is to be understood that this detailed description is not to be taken in a limiting 50 sense, since the scope of my invention is best defined by the appended claims.

Referring to the drawing:

Figure 1 is a wiring diagram of an automatic 55

control device or stabilizer incorporating my invention;

Fig. 2 is a wiring diagram showing another application of my invention, and especially to a regenerative type of electron emission amplifier; and

Fig. 3 is a graph illustrating the operation of the system shown in Fig. 2.

In Fig. 1 I show amplifier 11 in diagrammatic form, which is intended to operate on signal impulses and to increase the intensities thereof: for example, to amplify sounds reaching a microphone 24. I also show the outgoing circuit 12-13, carrying the amplified signaling impulses and capable of impressing said amplified impulses onto a succeeding amplifier or onto a translating device 23, such as a sound recorder, or loud speaker, or the like.

Interposed between amplifier 11 and circuit 12-13, is the amplification control device 14. This is in the form of a four armed Wheatstone bridge. The amplifier output connects across one diagonal thereof, and circuit 12-13 across the other. The bridge 14 is shown as formed of a series of four impedances, such as resistors 15, 16, 17, 18. If the ratio of impedance 15 to impedance 16 is the same as that of impedance 18 to impedance 17, it can readily be shown that the bridge is "balanced"; that is, that any potential difference impressed by the amplifier system across points 19, 20 will cause no potential difference to exist between points 21, 22, to which the circuit 12, 13 connects. Thus under such circumstances, no matter how great the amplification secured by the amplifier 11, this amplified signal is not made available in circuit 12-13.

However, if the prescribed ratios change, the bridge becomes unbalanced, and as the ratios depart more and more from the balanced condition, a greater effect is produced in circuit 12-13. The device 14 is so constructed and arranged that these ratios change automatically and continuously in response to variations in the intensity of the signals in the amplifier output. How this effect is secured will now be described.

Two opposite resistance arms such as 16, 18, of the bridge 14 are made from material such that any increase in temperature causes a very large increase in resistance. Such material may be iron wire, or manganin, or the like. These arms 16, 18, can be enveloped in tubes to conserve heat generated by the flow of current therethrough, so that the greater the current flow, the greater the temperature becomes, and consequently, the greater the resistance. The other two arms 15, 17 can be made from ordinary conducting wire.

It is apparent that the resistance can be so chosen that any desired controlling effect is secured. If the resistances 16, 18, are made from fine wire, they can respond more quickly to the variations in potential across points 19, 20 and the circuit 12-13 is correspondingly caused to respond quickly. On the other hand, the use of larger wire for these resistances causes a heat lag that may produce substantial lag in response in the circuit 12-13. This speed of response can also be modified by compassing the resistances 16, 18 in material of any desired heat conserving or insulating quality, to control the rate of heat dissipation from these resistances.

The various resistances are of course so designed that during normal operation of the system (that is, while no unusually loud signals are transmitted by amplifier 11), the bridge is unbalanced, and an E. M. F. exists across points

21, 22. As the intensity of the signal increases, resistances 16, 18 increase, and this increase serves to bring the bridge more nearly to balanced condition. There is a corresponding reduction in the ratio between the E. M. F. across points 21, 22, and that across points 19, 20. Thus even a very greatly increased signal effect serves only slightly to increase the E. M. F. across points 21, 22. In fact the constants of the design can be chosen actually to reduce the E. M. F. across these points upon too great an increase in the signal intensity in the output side of amplifier 11. The limit to which such a signal reduction can be carried is of course also determined by the radiation characteristic of the resistors 16, 18, 15

In Fig. 2 I show my invention used in conjunction with an electron emission amplifier 25 which is connected up to provide a feed-back effect. In this case, I show a conventional microphone circuit including a microphone 26, battery 27, and 20 primary winding 28, of a transformer 29. This circuit is shown merely as an example of one way in which signaling impulses are passed to the amplifier tube 25.

When the microphone 26 is caused to operate 25 in response to sounds reaching it, the resistance of circuit 26-27-28 varies in accordance with the sound waves, the current varies correspondingly, and an E. M. F. is induced across secondary coil 30. This E. M. F. is impressed 30 upon the input side of amplifier 25. For example, to accomplish this, the lower end of secondary 30 connects through a biasing battery 31 to the cathode 32; and the upper end connects through a variable potentiometer resistance 33 to 35 the control electrode 34. The potentiometer resistance can be varied by movement of a variable contact device 35. The output circuit of amplifier 25 includes plate or anode 36, primary coil 37 of a transformer 38, B battery 39, and filament 40 or cathode 32.

The variations in space current of amplifier 25, due to variations in E. M. F. applied to the input of amplifier 25 cause corresponding variations in E. M. F. in the secondary coil 40 of transformer 38. These varying E. M. F.'s can be impressed upon succeeding stages of amplifiers, such as indicated at 41, and finally upon a translating device 42, such as a recorder or loud speaker. The secondary coil 40 for this purpose 50 is connected by conductors 43, 44 to the amplifier 41.

The E. M. F. impressed upon the input side of amplifier 25 is to some extent dependent upon the output E. M. F. thereof. Thus for weak signals, the E. M. F. impressed across the input circuit is increased by the system I have evolved; and for strong signals, the E. M. F. is reduced thereby. There is, therefore, a stabilizing effect, tending to maintain the intensity of the output 60 E. M. F. substantially constant.

To secure this result, a Wheatstone bridge device 45 is included, of the same characteristics as device 14 of Fig. 1. The arms 47, 48 have a high temperature coefficient so that their resistances increase rapidly with increase in current flow, while the other two arms, 49, 50 are made from the usual kind of resistance wire. The output circuit of amplifier 25 is caused to affect the E. M. F. across the diagonal points 51, 52, 70 as by connecting these points respectively to conductors 43, 44.

When the ratio of resistance 49 to resistance 48 is the same as that of resistance 47 to resistance 50, then the E. M. F. across the other diag- 75

onal points 53, 54, is reduced to zero; if the resistances 47, 48 are less than required by these ratios, the points 53, 54 have a potential difference; and if the resistances 47, 48 are greater than required by these ratios, then the points 53, 54 have a potential difference of opposite sign. Thus this potential difference can be used to produce automatically either a regenerative or a reverse feed-back effect, depending upon the strength of the signal.

To secure this result, points 53, 54 can be connected to affect the potential drop across potentiometer resistance 33, any desired portion of which can be included in the input circuit of amplifier 25. Thus points 53, 54 can be connected to the primary coil 55 of a transformer 56, the secondary coil 57 of which is connected across resistance 33. It is apparent that by varying the position of tap 35 on resistance 33, any desired portion of the potential drop in resistance 33 can be included in the input circuit. The direction of this drop is chosen to be in phase with the E. M. F. across coil 30, when the signals are weak; and of course they are automatically caused to be out of phase when the signals are strong, due to the automatic selection of the E. M. F. across points 53, 54 as just explained.

Although rapidly varying currents flow through the circuits, yet the resistances 47, 48 can be readily caused to respond to them.

The controlling effect of the variable tap 35 is best illustrated in connection with Fig. 3. The ordinates of curves A, B, C represent output E. M. F.'s across points 51, 52. The abscissae represent input E. M. F.'s, say that existing across coil 30. Curve A shows a rising characteristic in general, the greater the input E. M. F. the greater the output E. M. F. Curve B shows a flat characteristic over a wide range, indicating no variation of output as the input E. M. F. varies; while curve C shows a characteristic that first rises to a maximum and then declines upon further increase in the input E. M. F. All these characteristics can be obtained by varying the position of contact 35.

It is apparent that I have provided a system that serves to prevent the production of undesirably intense signals, and yet without any danger of producing distortion.

I claim:

1. In an amplifier system for electric signal impulses, an amplifier, a Wheatstone bridge having resistance arms, means for impressing all the signaling impulses from the amplifier across a diagonal of the bridge, and an outgoing circuit connected across the other diagonal, the resistance of at least one of the arms varying directly with the current resulting from the intensity of the impressed signaling impulses, whereby the potential difference across said other diagonal is controlled in accordance with the said intensity.

2. In an amplifier system for electric signal impulses, an amplifier, a Wheatstone bridge having resistance arms, a pair of opposite resistance arms having a characteristic such that variations in current flow therein cause substantial variations in resistance in said arms, means for impressing all the signaling impulses from the am-

plifier across a diagonal of the bridge, and an outgoing circuit connected across the other diagonal.

3. The combination as set forth in claim 2, in which the resistance characteristic of said pair of opposite arms are so chosen that as the signal intensity increases, the ratio of the electromotive force passed by the bridge to the outgoing circuit, to the signaling electromotive force is reduced.

4. In a feed-back amplifier system for signaling impulses, an amplifier, an input and an output circuit therefor, a Wheatstone bridge having four resistance arms, one diagonal of the bridge being connected so as to be affected by the electromotive force in the output circuit, and the other diagonal being connected to a circuit coupled to the input circuit so as to affect the input circuit electromotive force at least one of the arms being constructed so that an increase in current flow therein causes a substantially large increase in resistance.

5. The combination as set forth in claim 4, in which the arms of the bridge are so proportioned that for weak signals the electromotive force across the said other diagonal serves to produce positive feed-back and for strong signals negative feed-back.

6. In a feed-back amplifier system for signaling impulses, an amplifier, an input and an output circuit therefor, a Wheatstone bridge having four resistance arms, one diagonal of the bridge being connected so as to be affected by the electromotive force in the output circuit, a circuit including a potentiometer, a circuit coupled to said potentiometer circuit and connected across the other diagonal of said bridge, and means whereby the potentiometer may variably affect the input circuit, at least one of the arms being constructed so that an increase in current flow therein causes a substantially large increase in resistance.

7. The combination as set forth in claim 6, in which the arms of the bridge are so proportioned that for weak signals the electromotive force across the said other diagonal serves to produce positive feed-back, and for strong signals, negative feed-back.

8. In a feed-back amplifier system for signaling impulses, an amplifier, an input and an output circuit therefor, and means for interconnecting the input and output circuits to secure a feed-back, said means including a Wheatstone bridge across one diagonal of which the output circuit is connected, and a coupling circuit connected across the other diagonal of the bridge and inductively coupled to the input circuit, at least one of the impedances of the bridge increasing in value with an increased current flow therethrough, the bridge impedances cooperating to cause a reversal of potential across the second diagonal with respect to the first diagonal when a potential difference exceeding a predetermined maximum potential difference is impressed across the first diagonal, whereby the energy fed by the coupling circuit to the input circuit reverses in direction when the energy in the output circuit increases beyond a definite value.

FRANK RIEBER.
